UNITED STATES PATENT OFFICE.

CHRISTOPHER LORRANCE ANTON, OF MONONGAHELA, PENNSYLVANIA.

DRILL.

1,082,617.

Specification of Letters Patent. Patented Dec. 30, 1913.

Application filed May 15, 1913. Serial No. 767,846.

To all whom it may concern:

Be it known that I, CHRISTOPHER LORRANCE ANTON, a citizen of the United States, residing at Monongahela, in the county of Washington and State of Pennsylvania, have invented certain new and useful Improvements in Drills, of which the following is a specification, reference being had to the accompanying drawings.

10 This invention relates to improvements in drills, and more particularly to that class of drills which are adapted for use in connection with coal mining.

An object of this invention is the provision of a drill of this character which is provided with a plurality of removable bits, so that the bits may be readily detached from the drill head when it is desired to sharpen the same.

20 Another object of this invention is the provision of a drill comprising a head having a socket formed therein, a central bit arranged in the socket, the central bit projecting outwardly beyond the pairs of bits 25 arranged in the opposite ends of the socket, the central bit being adapted to start a hole, and the side bits cutting a hole of the desired diameter.

25 A still further object of this invention is the provision of a drill comprising a head having a socket formed therein, the head being also provided with a reduced tubular extension, a central bit disposed in the socket, and said bits arranged in the opposite ends of the socket, the central bit having a reduced threaded extension projecting through the extension of the head, and a nut threaded on the extremity of the extension of the central bit to bear against the 40 extremity of the extension of the head, whereby the several bits are maintained in position in the head.

With these and other objects in view, my invention consists in the novel construction, combination and arrangement of parts, to be hereinafter more fully described, claimed and illustrated in the accompanying drawing, in which—

50 Figure 1 is an elevation of my device, partly in section; Fig. 2 is an elevation of the central bit; Fig. 3 is an elevation of one of the side bits; and Fig. 4 is an end view of the head with the bits removed.

55 Referring more particularly to the drawing, the numeral 5 designates the drill head

which is provided with a rearwardly projecting tubular extension 6, whereby the head may be secured to any desired construction of drill stock, (not shown). The head 5 is provided with an elongated bore or socket 7 which communicates at one end with a bore of the tubular extension 6, and the bore is enlarged laterally and centrally thereof, as at 8, to afford recesses adapted to receive the side faces of a central cutting bit 9 whereby the same is maintained against axial movement. The reduced extension 6 forms a shoulder 10 at the inner end of the head, and the central bit 9 is provided with a reduced threaded extension 11 which is 60 adapted for engagement in the bore of the extension 6 and projects therethrough. Arranged in the opposite sides of the socket 7 are side bits 12, the inner ends of the bits 65 engaging the shoulder 10 whereby the inward movement thereof is limited. The opposite faces of the central bit 9 are beveled, as at 13, and the inner faces of the bits 12 are beveled as at 14, at their inner ends, the beveled surfaces of the bit 9 being adapted 70 to engage the beveled inner faces of the side bits 12 to maintain them in position within the head.

75 The forward extremity of the central bit is formed with a pair of reversely extending cutting teeth 15, the teeth projecting beyond the outer ends of the bits 12 which are curved outwardly, as at 16, to space the same from the opposite faces of the bit 9. It will be seen that several sets of side bits 12 may 80 be used in connection with the drill, the bits being curved outwardly to relatively different degrees, whereby openings of any desired diameter may be formed in the wall of the mine. The outer face of the head 5 is 85 formed with diametrically opposite obliquely extending shoulders 17, which are adapted to feed the slack or dirt cut by the bits rearwardly of the head.

90 In the practical use of my device, when it is desired to connect the several bits to the head, the side bits 12 are arranged in the opposite sides of the socket 7, and the bit 9 is disposed between the side bits, so that the reduced extension 11 thereof projecting 100 through the bore of the extension 6, and the beveled surfaces 13 on the opposite faces of the central bit engage the beveled inner faces of the bits 12. A nut 18 is threaded upon 105 the projecting extremity of the extension 11, 110

the nut being adapted to bear against the reduced extension 6 thereby serving to create the requisite endwise adjustment of the bit 9 to lock the side bits in operative position within the head. From the above description taken in connection with the accompanying drawing, it will be seen that should any of the bits become broken or dull, they may be readily removed by disengaging the nut 18 from the extension 11 of the central bit, whereby new or sharpened bits may be readily secured in the head.

Having thus fully described my invention what I desire to claim and secure by Letters Patent is:

1. A drill comprising a head having a socket therein, the opposite walls of such socket being provided with alined recesses, a bit adapted to be arranged centrally in said socket and extending within the recesses whereby such bit is held against axial movement, auxiliary bits arranged within said socket between the ends thereof and the central bit, said central bit and auxiliary bits being provided with coacting means where-

by the same may be maintained in operative position relatively to the head.

2. A device of the character described comprising a hollow head having a tubular extension, a bit arranged centrally within said head and having a reduced extension projecting through said tubular extension, auxiliary bits arranged within said head upon opposite sides of the central bit, the opposite faces of said central bit being beveled intermediate of its ends, the inner faces of said side bits being beveled for engagement with the beveled faces of said central bit, means mounted upon the extremity of the reduced extension of said central bit to maintain said bits within said head, said central bit and the inner walls of the head being provided with coacting means to hold said central bit against axial movement.

In testimony whereof I hereunto affix my signature in the presence of two witnesses.

CHRISTOPHER LORRANCE ANTON.
